UNITED STATES PATENT OFFICE.

FRANCIS L. BAIN, OF EVERETT, MASSACHUSETTS.

DESK AND CHAIR COMBINATION.

1,182,621.

Specification of Letters Patent.

Patented May 9, 1916.

Application filed June 23, 1915. Serial No. 35,865.

To all whom it may concern:

Be it known that I, FRANCIS L. BAIN, a citizen of the United States, residing at Everett, in the county of Middlesex and 5 State of Massachusetts, have invented new and useful Improvements in Desk and Chair Combinations, of which the following is a specification.

This invention relates to school furniture 10 and more particularly to combined chair and desk mountings.

The principal object of the invention is to provide a unitary structure which is simple, cheaply constructed, durable and efficient and which embodies novel features of adjustment and support for the various parts.

Further objects of the invention will appear as the following specific description is 20 read in connection with the accompanying drawing which forms a part of this application, and in which:

Figure 1 is a side elevation. Fig. 2 is a vertical sectional view. Fig. 3 is a horizontal section showing in bottom plan view the 25 seat and desk casting.

Referring more particularly to the drawing, 1 represents a base which is substantially H-shaped in plan and which is provided 30 adjacent opposite ends with raised bosses 2 and 3 centrally recessed or apertured as shown at 4 and 5 to receive the seat and desk standards 6 and 7 respectively. Each of these standards is tubular and has 35 slidably mounted therein an extension standard 8 upon which is adjustably mounted an inverted cup-shaped collar 9 held in position by a set screw 10 and surrounding the main standard 6 or 7 with an interposed metallic washer 11 preferably of lead, babbitt 40 or other similar material. The lower edge of the cup fits in an annular recess 12 formed in a cup-shaped collar 13 adjustably secured upon the main tubular standard 6 or 7 by 45 a set screw 14. The upper end of the extension standard 8 for the desk has secured thereto a spider-like casting 15 secured to the underneath side of the seat 16 while the extension 8 of the desk standard has secured

thereto a crescent-shaped casting 17 which 50 is bolted to the underneath side of the desk 18. The castings 15 and 17 may be secured on the respective extensions by a set screw 19 or may be formed as an integral part thereof, if desired. As shown, the lower 55 edge of the cup-shaped collar 9 rests upon a washer 20 which is interposed between the lower edge of the cup and the base of the recess 12. The extension standard 8 therefore 60 has a two-point support, i. e. upon the upper end of the tubular standard 6 or 7 and upon the cup collar 13. Also the extension is laterally braced by reason of the overhang of the collar 9 engaging the side walls of 65 the standards 6 or 7.

The standards 6 and 7 may be secured within the sockets 4 and 5 in any suitable manner such as by shrinking or sweating and the parts may assume any desired dimension or be of any suitable material without departing from the spirit or scope of the 70 invention.

What is claimed is:—

A device of the character described including a base having an upright tubular boss, a 75 tubular standard fitted and secured at its lower end in said boss, a collar adjustably mounted upon said standard and provided with an annular groove in its upper edge, a packing seated within said groove, a set 80 screw securing said collar to the tubular standard, an extension standard slidably mounted in the tubular standard, an inverted cup-shape collar slidably mounted upon the extension standard and having 85 its depending flange fitted within the groove of the first-named collar and engaging said packing, packing within said second collar, and a set screw for adjustably securing said second collar to the extension 90 standard.

In testimony whereof I affix my signature in presence of two witnesses.

FRANCIS L. BAIN.
